US00D438131S

(12) **United States Design Patent** (10) Patent No.: **US D438,131 S**
Kim et al. (45) Date of Patent: ** Feb. 27, 2001

(54) **IDENTIFYING UNIT FOR DETECTING THE IRIS**

D. 429,175 * 8/2000 Ha D10/104

* cited by examiner

(75) Inventors: **Bum Chul Kim; Jang Jin Chae**, both of Kyungki-do (KR)

Primary Examiner—Marcus A. Jackson

(73) Assignee: **LG Electronics Inc.**, Seoul (KR)

(57) **CLAIM**

(**) Term: **14 Years**

The ornamental design for an identifying unit for detecting the iris, as shown and described.

(21) Appl. No.: **29/120,290**

DESCRIPTION

(22) Filed: **Mar. 17, 2000**

FIG. 1 is a perspective view of the an identifying unit for detecting the iris;

(51) LOC (7) Cl. **10-05**

FIG. 2 is a front view thereof;

(52) U.S. Cl. **D10/104; D14/102**

FIG. 3 is a rear view thereof;

(58) Field of Search D10/104, 121;

FIG. 4 is a left side view thereof;

D14/102; D24/172; 351/232, 237, 239,

243, 244; 340/540, 571, 572, 573

FIG. 5 is a top plan view thereof; and,

(56) **References Cited**

FIG. 6 is a bottom plan view thereof.
